UNITED STATES PATENT OFFICE.

ALBERT H. SMITH, OF DARBY, PENNSYLVANIA.

INTERCHANGEABLE TOOTH.

1,334,119.

Specification of Letters Patent. Patented Mar. 16, 1920.

Application filed November 12, 1918. Serial No. 262,154.

To all whom it may concern.

Be it known that I, ALBERT H. SMITH, a citizen of the United States, residing at Darby, in the county of Delaware and State 5 of Pennsylvania, have invented new and useful Improvements in Interchangeable Teeth, of which the following is a specification.

My invention relates to a new and useful 10 improvement in an interchangeable tooth, and has for its object to provide in combination with an artificial tooth an exceedingly, simple, effective, strong and durable anchoring means whereby said tooth may be 15 attached to a vulcanite plate or artificial palate.

A further object of the invention is to provide an artificial tooth with two parallel 20 sockets extending from the ridge lap, each having a mouth leading rearwardly to the lingual face of the tooth the mouths being of less length than the sockets and the partition between said sockets having horizontal 25 grooves for registration with parts of an anchoring device arranged to fit in said sockets and adapted to be embedded in an artificial palate.

A further object of the invention is to provide an anchoring device or means of unique 30 construction having a loop portion for embedding in a vulcanite plate from which project two legs each having a foot for registration with the sockets of the tooth, said legs preferably being flattened and having 35 corrugations formed therein to co-act with the horizontal grooves or notches in the partition between the sockets.

With these ends in view, this invention 40 consists in the details of construction and combination of elements hereinafter set forth and then specifically designated by the claims.

In order that those skilled in the art to which this invention appertains may understand how to make and use the same, I will 45 describe its construction in detail, referring by numerals to the accompanying drawing forming a part of this application, in which:

50 Figure 1, is a perspective view of a tooth constructed in accordance with my invention.

Fig. 2, is a section at the line 2—2 of Fig. 1.

55 Fig. 3, is a transverse section at the line 3—3 of Fig. 2.

Fig. 4, is a plan view or end view of the tooth looking at the ridge lap end showing the anchoring device connected therewith.

Fig. 5, is a section at the line 5—5 of 60 Fig. 4.

Fig. 6, is a perspective view of one form of anchoring device.

In carrying out my invention as embodied in Figs. 1 to 6 inclusive 65 2 represents an artificial tooth embodying all the essential features of the ordinary artificial tooth for use with a vulcanite plate or artificial palate and includes a ridge 3, a lingual face 4 and an incisal edge 15.

In the body of this tooth is formed a pair of parallel longitudinal sockets 6 of any desirable cross-section and from which lead narrow mouths or communicating transverse slots 7 and in certain of the walls of said slots, preferably the inside ones, or the partition 8 between the two mouths or slots are formed horizontal grooves or channels 9. The mouths or transverse slots leading from the sockets are preferably of less length 80 than the latter so that portions of said sockets project beyond the closed ends of the transverse slots or mouths toward the incisal edge to produce socket extensions 10.

Constructed to fit the pair of sockets of 85 the tooth is an anchoring device 11, comprising a loop portion or section 12 from which project the pair of legs 13 adapted to register with the transverse slots 7, each leg having a foot 14 at its end for registration 90 with the sockets 6. Although the anchoring device may be formed in any desirable shape, of metal having any suitable cross-section I prefer to form the same so that the loop portion or section 12 is circular in 95 cross-section while the legs 13 are flattened throughout the major portions of their lengths and blend into the circular cross-section of the loop portion, said flattened legs having concavo-convex ribs or corrugations 100 15 for registration with the horizontal grooves 9 while the feet 14 are preferably circular in cross-section to fit sockets 6 with both ends of each foot projecting beyond or above and below each leg so that when the 105 anchoring device is in place one end of each foot projects into the socket extension 10 of the socket as will be readily understood.

The anchor 11 is also preferably made of metal having sufficient resiliency to maintain the feet 14 in approximately constant 110 relation, the normal space between which

will be slightly less than the thickness of the partition 8, so that when the anchor is attached to the tooth the ribs 15 will be forced into the grooves 9 so as to prevent 5 the accidental withdrawal of the anchor, making it necessary to provide means for holding parts together for sale or shipment.

The grooves or channels 9 are distributed over the walls of the slots and are of sufficient number so that the anchoring device 11 may be held in any of a number of different 10 positions so that the distance between the anchor and the incisal edge may be varied according to the requirements of the particular 15 person to whom the teeth are being fitted and in accordance with said person's bite. The corrugations or ribs 15 may be one or more in number and besides co-operating with the grooves or channels 9 to position 20 the anchor, also strengthen the legs of the anchor in the region of the flattened portions thereof and in practice the said flattened portions are so formed that the edge toward the ridge lap end of the tooth is on 25 an angle while the other edge or that toward the incisal edge of the tooth is straight or in alinement with the outer surface of the anchor loop.

After the proper teeth have been selected 30 and a mold set up for molding the vulcanite plate or artificial palate the teeth with their anchors are properly positioned in the mold with the loops projecting rearwardly outside of the teeth so that when the vulcanite plate is formed said loops will be embedded 35 in said plate while a certain amount of the vulcanite material will enter the sockets 6, the mouths or slots 7 communicating therewith and thus secure the anchors in their 40 respective teeth, thereby forming a plate having all the appearances of the ordinary plates in use at the present time.

If from any cause whatsoever a tooth 45 constructed in accordance with my improvement is broken the same may be further broken or cut away so as to entirely remove it from its anchor, after which a duplicate tooth is interchangeable with the original one and may be placed on the anchor by 50 bringing the open ends of the sockets and the ridge lap into registration with the feet of the anchor and then sliding said tooth to its proper position after which the cavities, chambers or spaces in the sockets and their 55 communicating slots about the anchor may be filled with a suitable cement indicated by the numeral 16 in Figs. 4 and 5.

By providing the tooth with two sockets the strain incident to eating or chewing is 60 distributed over a greater space or surface

reducing to a minimum the possibility of the tooth cracking or breaking through ordinary use, whereas it has been found that by the use of a single socket in a heavier tooth, such as a molar, the tooth being weakened along the one line and the strain being against a very small surface or along one wall, such a tooth will often split or break in half along the longitudinal center. Further by making the feet of the anchor so 65 that they are relatively long and have a bearing upon a considerable surface, the tooth will be prevented from wobbling endwise while the two feet prevent the tooth from moving sidewise or rotating and as 70 these movements are prevented it is very unlikely that said tooth will work loose. 75

Of course I do not wish to be limited to the exact details of construction as herein shown as these may be varied within the 80 limits of the appended claims without departing from the spirit of my invention.

Having thus fully described my invention, what I claim as new and useful is:—

1. An interchangeable tooth comprising a 85 body having a pair of parallel sockets each having a narrow mouth or slot leading therefrom, in the side walls of which are formed horizontal grooves or channels and an anchor comprising a loop portion for embedding in a vulcanite plate, a pair of legs flattened to fit the slots and having ribs or corrugations to engage the grooves or channels and a foot at the end of each leg for registration with the sockets. 90

2. A tooth comprising a loop portion for embedding in a vulcanite plate, a pair of legs projecting therefrom having flattened portions one edge of each of said flattened portions being straight and in alinement 100 with a portion of the outer circumference of the loop, the other edges being angular or diverging from the straight edge away from the loop and a foot at the end of each leg: 105

3. A tooth anchor comprising a loop portion for embedding in a vulcanite plate, a pair of legs projecting therefrom having flattened portions, one edge of each of said flattened portions being straight and in alinement with a portion of the outer circumference of the loop, the other edges being angular or diverging from the straight edge away from the top, said flattened portions having ribs or corrugations and a foot 110 at the end of each leg, the ends of each foot 115 projecting above and below its respective leg.

In testimony whereof, I have hereunto affixed my signature.

ALBERT H. SMITH
